UNITED STATES PATENT OFFICE.

ROY M. UPTON, OF RUTHERFORD, NEW JERSEY, ASSIGNEE OF ONE-HALF TO THOMAS J. NORTON, OF RUTHERFORD, NEW JERSEY, AND ONE-HALF TO UPTON CARBURETOR COMPANY, INC., A CORPORATION OF NEW YORK.

CARBURETER.

1,301,623.

Specification of Letters Patent. Patented Apr. 22, 1919.

Application filed October 12, 1914, Serial No. 366,209. Renewed September 12, 1918. Serial No. 253,350.

To all whom it may concern:

Be it known that I, Roy M. Upton, a citizen of the United States, and resident of Rutherford, in the county of Bergen and State of New Jersey, have invented certain new and useful Improvements in Carbureters, of which the following is a specification.

My invention has reference more particularly to carbureters for use on internal combustion engines, and has for one object to provide simple and efficient means for the production of the mixture at varying engine speeds, and has for another object to provide simple and efficient means to enable operation of the needle valve for the liquid fuel to be variably controlled with the main throttle valve.

My invention comprises novel details of improvement and combinations of parts that will be more fully hereinafter set forth and then pointed out in the claims.

Reference is to be had to the accompanying drawings forming part hereof, wherein,

Figure 1 is a plan view, partly in section, of a carbureter embodying my invention; Fig. 2 is an end view of Fig. 1; Fig. 3 is an enlarged section on the line 3-3, in Fig. 1, and Fig. 4 is a detail perspective view.

Similar numerals of reference indicate corresponding parts in the several views.

In the embodiment of my invention illustrated in the accompanying drawings, I provide a casing having a fuel chamber 1, a carbureting chamber 2 and an air intake passage 3. Suitable means, such as a float 4, controlling a valve 5, are provided for maintaining a constant level in the fuel chamber.

At 6 is a passage providing communication between fuel chamber 1 and the carbureting or mixing chamber 2, the upper orifice of which passage is shown leading to an annular channel or groove 7, shown provided at the inner wall of chamber 2. The normal level of fuel may be maintained in said channel surrounding the air that flows upwardly through the mixing chamber within said channel. At 8 is a needle valve controlling the flow from chamber 1 to the carbureting chamber, said needle valve being shown provided with threads 8^a meshing in corresponding threads in the tubular portion 9, the lower end of said valve engaging a seat 10 com-

municating by port 11 with the float chamber. At 12 is a weighted air-controlling valve, shown tapering upwardly and downwardly, substantially in double conical form, having its greatest transverse diameter (at 12^a) located substantially on the plane of channel 7, and providing a normally relatively narrow annular space at 13 between the edge of channel 7 and the edge 12^a of said valve for the flow of air therebetween, and whereby as said valve rises the space between said valve and the inner edge of channel 7 will be increased for the passage therebetween of more air, as the downwardly tapering portion of the valve rises, and whereby such flow of air will be restricted as the valve 12 descends, in accordance with requirements. Said valve 12 is guided to rise and fall due to variations of engine suction, and for this purpose, as well as to provide a convenient means to aid in lifting said valve and resisting its descent, I provide the following arrangements: At 14 is a tubular standard slidably receiving the annular recess 15 in the lower part of valve 12, the central downwardly disposed stem 16 of which valve slides within the bore 14^a of said standard. Within said bore is a spiral spring 17, seated against the bottom of said bore, and bearing at its upper end against the stem 16, the tension of such spring being such that the weight of valve 12 will compress said spring to allow the valve to normally seat against the top of standard 14, but when said valve is raised by reason of the engine suction, said spring will aid in lifting the valve, thereby counterbalancing a portion of the weight of the valve. The bore 14 communicates by a port 18 with chamber 1, being shown communicating with a passage 19 in the casting, whereby liquid fuel may flow from chamber 1 into bore 14^a, such parts thereby acting in the nature of a dash-pot, the fuel in bore 14^a serving to resist sudden dropping of valve 12 when throttle 20 is suddenly closed.

The upper portion 21 of the carbureter having the mixing chamber has suitable bearings receiving the shaft 22, to which throttle valve 20 is secured, for controlling the flow of mixture from the mixing chamber. At 21^a is a cover fitting over chamber 1. Said parts may be secured together by screws, as shown. Above channel 7 and be-

low throttle 20 the part 21 is shown provided with a stop 23, in position to enable valve 12 to rise the required distance, and around said stop are several openings 23^a formed between arms or branches 23^b of the casting, to which arms the stop 23 is connected, which arms or branches are shown upwardly and outwardly inclined. The side surfaces 23^c of said arms are also shown inclined upwardly at an angle to the vertical. The mixture of liquid fuel and air is caused to travel in several streams through the openings 23^a, being diverted with a sort of swirling motion to more finely break up the mixture.

The needle valve 8 may be set for the desired supply of fuel to the carbureting chamber for ordinary running conditions, and in order to enable said valve to be opened more widely at certain throttle openings, as when the throttle 20 is wide open or nearly so, I provide the following arrangement: At 24 is an arm adapted to be secured in set position upon needle valve 8, as by the screw 25 clamping the split end of arm 24 securely upon said needle valve. Between arm 24 and shaft 22 I provide devices for moving said arm as required. To this end I have shown a rod 26, connected with arm 24, and slidable in a cylinder or bore 27 in a member 28 that is connected with the throttle arm 29 secured upon shaft 22 in an ordinary manner. The rod 26 is connected with arm 24 by a suitable swivel or ball-and-socket joint of well known character, indicated at 26^a, and the member 28 is similarly connected with arm 29 by a swivel or ball-and-socket joint 30. The rod 26 is shown screw threaded to fit securely in member 26^a and is shown provided with a stop for the member 28, said stop being shown in the form of nuts 31, whereby said nuts may be set and secured along rod 26 in desired position to engage the member 28. The arrangement is such that arm 24 may be normally held against a stop 32 by a suitable spring 33, and the rod 26 will have free play in bore or cylinder 27 for the full throw of throttle arm 29, when the nuts 31 are set at the greatest distance from member 28, as illustrated in Fig. 1, so that in such case the throttle 20 may be operated without in turn operating valve 8. If, however, it is desired to cause valve 8 to open at or near the termination of the full opening of throt-

tle 20, the nuts 31 will be set along the rod 26 a suitable distance to cause said nuts to be engaged by member 28, sooner or later, after throttle 20 has opened to a desired extent, to cause arm 24 to be moved to the right in Fig. 1, to thereby rotate needle valve 8 to more or less move the valve from its seat 10 to then admit more fuel to passage 6. By this means an increase of fuel supply to carbureting chamber 2 may be effected for high speeds of the engine, as for running on open or nearly open throttle, without affecting the set position of needle 8 for ordinary throttle openings.

Changes may be made in the details of construction and arrangements of parts shown and described, as the same may be varied, within the scope of the appended claims, without departing from the spirit of the invention.

Having now described my invention what I claim is:

1. In a carbureter, a casing having a fuel chamber, a carbureting chamber, a passage providing communication between said chambers, a standard extending toward the carbureting chamber and having a bore opening at its upper end, a valve having a recess receiving said standard and having a stem entering said bore whereby said valve is guided to rise and descend upon said stem relatively to said passage, and a spring within said bore bearing against said stem and normally compressed by said valve.

2. In a carbureter, a casing having a fuel chamber, a carbureting chamber, a passage communicating with the fuel chamber and having an orifice communicating with the carbureting chamber, a mixing chamber, a series of arms within the mixing chamber spaced above said orifice and having a stop, said arms providing spaces therebetween, the side surfaces of said arms being inclined upwardly at an angle to the vertical to divert the mixture flowing from the carbureting chamber, a valve to coact with said stop, and a throttle above said arms.

Signed at New York city, in the county of New York, and State of New York, this 9th day of October, A. D. 1914.

ROY M. UPTON.
